LETTER OUTLINING TEMPLET

Herbert De Oslund, Minneapolis, Minn.

Application February 9, 1933, Serial No. 655,873

3 Claims. (Cl. 33—174)

My invention provides an extremely simple and highly efficient templet for outlining letters, figures and like characters, and generally stated, consists of the novel construction and arrangement of parts hereinafter described and defined in the claims. The device is adapted to be stamped from sheet metal and may be marked, punched and graduated by the same or separate operations.

10. The templet is formed with three approximately parallel arms. The two outer arms at one end are connected by an elbow or main cross-connection, while one of said outer arms is connected to the intermediate arm by a smaller elbow or cross-connection. The intermediate arm terminates close to the main elbow but is spaced therefrom far enough to permit a pencil point or the like to pass therebetween. The other outer arm has a curved end that terminates close to the smaller elbow but is spaced therefrom far enough to permit the point of a pencil or the like to be passed between the same. The several arms are perforated to provide pivot points, as will hereinafter more fully appear.

25. The improved templet is illustrated in the accompanying drawing wherein like characters indicate like parts throughout the several views.

Referring to the drawing:

Fig. 1 is a plan view showing the templet;

30. Fig. 2 is a plan view showing the templet and illustrating its use in outlining the letter "S"; and

Fig. 3 is a plan view showing the templet and illustrating its use in outlining the letter "W."

35. Of the three arms of the templet above indicated, the two outer arms are indicated by the numerals 4 and 5, while the intermediate or central arm is indicated by the numeral 6. The two arms 4 and 5 at one end are connected to the main elbow or cross-connection 7 while the other end of the arm 4 is connected to the arm 6 by a small elbow 8. The free end of the arm 6 is spaced from the main elbow or cross-connection 7 to form a narrow passage 9. The free end of the arm 5 is curved and spaced from the smaller elbow 8 to form a narrow passage 10. It is important to note that the smaller elbow 8 and the end of the arm 5 are struck on the arc of a circle, both at their inner and outer edges, thus giving curves of varying sizes.

50. In using the templet, the following information will be of value:

55. 1. The height of all letters or like characters can and should be gauged by the outside width of the templet, so the first step in the making of

any character is the laying of the templet lengthwise and outlining its outside edges.

2. The next step in the formation of all letters with perpendicular legs or sides, is the laying of the templet so that the horizontal line 10—x, which intersects the pivot points 14 and 19 at right angles, is parallel to the upper guide line. This is of importance so that the pivot points will be at their proper positions for striking the desired angles.

10. 3. All oblique lines are used as guides in determining the proper slant of the characters or parts thereof, or in ascertaining the angle at which the templet should be allowed to come to rest when in pivotal movement.

15. 4. The distance between the parallel, horizontal lines 10—x and 10—y is equal to the distance between the outside edges of the arms 4 and 5, and any side of the square thus formed is divided into five equal divisions. This is very important as the letters of the alphabet are of various uniform width, ranging from one division in the case of the "I" to five divisions in the instance of the "W."

20. To further assist in the formation of various 25 different letters or characters, the arm 4 is shown as provided with small perforations 11, 12, 13, 14 and 14'; the arm 5 is provided with small perforations 15, 16, 17, 18 and 19; and the arm 6 is provided with small perforations 20, 21, 22 and 30

25. 35. 23. These perforations 11 to 23, inclusive, afford pivot points, certain of the uses of which will be hereinafter noted. To guide the user in setting the templet at the proper angle for forming different letters, the arm 4 is shown as provided with transversely crossed lines 24—24 that intersect the perforation 14 and with other transversely intersecting lines 25—25. For a similar purpose, the arm 5 is provided with transversely intersecting angle-indicating lines 26—26 and 40 27—27. All three arms, at longitudinally spaced intervals, are formed with cross lines 28 that are at right angles to the respective arms. The central arm 6 is provided with a slightly oblique angle-indicating line 29 that intersects that perforation 23. The curved end of arm 5 is provided with an oblique line 30. For use in marking or outlining certain characters such as the numeral "5", the main elbow 7 is formed with an approximately L-shaped slot 31.

45. 50. In the formation of different letters, various different manipulations of the templet will be required, but it is thought sufficient to illustrate the use in forming two letters of very different outline, to wit: the letters "S" and "W". In the 55

use of the templet to form the letter "S", the templet is first placed in position to draw parallel horizontal lines indicated by the broken lines marked *a* on Fig. 2, and then the templet is then placed in the position indicated by full light lines at the right in Fig. 2, so that the line 29 is perpendicular. Then a portion of the letter "S" is outlined, as indicated by heavy full lines in Fig. 2. Here it will be noted that the proper cut-off 10 for the lower portion of the letter "S" will be marked by terminating the full lower lines when they reach the point indicated by the oblique line 30 on arm 5. When this is done, the pencil point or the like will be placed through the perforation 23 and the templet will be rotated to the left to the position indicated by dotted lines in said Fig. 2. Then the letter "S" is completed by drawing lines indicated by the heavy dotted lines in Fig. 2; and here it will be noted that the upper terminal of the letter "S" is indicated by terminating the said dotted lines again at said line 30. Thus the complete letter "S" may be quickly and accurately outlined.

In using the templet to outline the letter "W", the outer edges thereof will first be utilized to draw parallel horizontal lines *b*—*b*, which indicate and determine the height of the letter. Then the templet is turned to an angular position shown by light full lines on Fig. 3, setting the templet so that one of the lines 26 will be parallel with the upper line *b*. Then the first part of the letter "W" is outlined by marking as indicated by the heavy full lines in said figure. Then a pencil point or the like will be inserted through the perforation 15 and the templet is turned until the other cross line 26 aligns with the upper line *b*, as indicated by dotted lines in Fig. 3. Then the completion of the outlining of the letter is made by marking as indicated by the heavy dotted lines in said Fig. 3. Of course, the upper and lower guide lines *b* give the proper lines for termination of the upper and lower portions of the letter.

In forming other letters or characters, similar but different combinations of manipulations will be required. To describe all of the possible uses thereof, would require many pages, but it is thought that the illustrations given are sufficient to establish the utility of the templet. In forming certain characters such as the numeral "5", the slot 34 will be found useful in producing such character with a narrow vertical stem, part of which stem will be produced by running a pencil through the said slot 34. For forming ordinary letters, such as required for sign lettering, the several arms of the templet will, as stated, be usually made approximately parallel. Nevertheless, this structure may be varied. The said

arms might have a curved relation to each other, providing there is provided three arms, portions or members with two thereof terminated close to but slightly spaced from adjacent members, so as to permit a pencil or mark to be moved through the narrow passages provided by such spacing.

The perforation 21 in the structure shown in Fig. 1 serves as a pivot on which the device can be turned to different angles for the formation of different letters, such, for example, as "m" and "w".

From what has been said, it will be apparent that the device described is capable of various other modifications within the scope of the invention herein disclosed and claimed.

What I claim is:

1. A letter or character outlining templet comprising outer and intermediate substantially straight and parallel arms, said outer arms being connected at one end by a main elbow, and one of said outer arms and the intermediate arm being connected at one end by a smaller elbow, the other end of said intermediate arm being spaced from said main elbow to afford a narrow marker passage, the free end of the other outer arm being curved and terminated close to but spaced from said smaller elbow to afford a marker passage, all edges of said three arms being parallel.

2. A letter or character outlining templet comprising outer and intermediate substantially straight and parallel arms, said outer arms being connected at one end by a main elbow, and one of said outer arms and the intermediate arm being connected at one end by a smaller elbow, the other end of said intermediate arm being spaced from said main elbow to afford a narrow marker passage, the free end of the other outer arm being curved and terminated close to but spaced from said smaller elbow to afford a marker passage, said small elbow and the curved inner end of said outer arm having inner and outer edges that follow the lines of a true circle.

3. A letter or character outlining templet comprising outer and intermediate substantially straight and parallel arms, said outer arms being connected at one end by a main elbow, and one of said outer arms and the intermediate arm being connected at one end by a smaller elbow, the other end of said intermediate arm being spaced from said main elbow to afford a narrow marker passage, said intermediate arm having a perforation located midway between the extreme end portions of said templet and indicating a pivot on which the templet should be turned for the formation of different characters.

HERBERT DE OSLUND.
